INVENTOR:
Walter C. Beckwith,
By Theron Hall Atty

UNITED STATES PATENT OFFICE.

WALTER C. BECKWITH, OF FOSTORIA, OHIO.

BANK VAULT AND SAFE PROTECTOR.

1,408,494.

Specification of Letters Patent.

Patented Mar. 7, 1922.

Application filed January 29, 1921. Serial No. 440,831.

To all whom it may concern:

Be it known that I, WALTER C. BECKWITH, a citizen of the United States, residing at Fostoria, in the county of Lucas and State 5 of Ohio, have invented certain new and useful Improvements in Bank Vault and Safe Protectors; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

In attacks by burglars upon safes and bank-vaults, the usual practice is,—when the combination-lock cannot be mastered,—to knock off the knob of the permutation lock, 20 thus uncovering an opening in the door of the vault or safe, through which may be introduced a high explosive which, when exploded, blows open and wrecks the door. The object of the present invention is to prevent 25 the improper opening of the door as well as to render the permutation lock inaccessible, save to one having a proper key.

In carrying out my invention, I avail myself of the recent marked advance in the 30 knowledge of the chemistry of toxic gases and the art of their production. The gas or vapor to be employed in connection with my invention is a matter of selection, depending upon the degree of virulence desired, 35 and ranging from the well known "mustard" gas to, say, hydrocyanic acid vapors. These gases or vapors are confined, under such pressures as may be desired, in a container of frangible or easily ruptured material, and of such construction and contour 40 as will permit it to be secured in the path of a swinging door and as a shield for the door-lock.

To these ends my invention consists of a 45 construction of which a preferred embodiment is illustrated in the accompanying drawings, wherein—

Figure I, is a front-elevation of my device in operative position upon a vault door 50 or safe door; Fig. II, a transverse section of the same taken on line *a*—*a* Fig. I; Fig. III, a cross-section of the same taken on line *b*—*b* Fig. I; Fig. IV, an end-view of the same, seen from the left in Fig. I; Fig. V, a sectional 55 elevation taken on line *c*—*c* Fig. III and on

line *d*—*d* Fig. VI, and Fig. VI, a side-elevation of my device with parts hereinafter referred to indicated in dotted lines.

Like reference characters represent like parts throughout the several views.

In the drawings, 1 is a vessel of frangible material, such as glass or glazed porcelain or of thin sheet metal, the contour of the inner and outer walls being indicated in Figs. II, 60 III and IV. This vessel is charged with a suitable toxic fluid as hereinbefore indicated. The inner side of the vessel is chambered, as indicated in Figs. II and VI, in such manner as to receive and conceal the knob and disc *a* of the permutation lock. 2 is a 65 metal block securely fastened, as at 3, to the jamb *b* of the door *c*, or in case of double doors, to the margin of the companion door. Through this block are two horizontal holes 4—4. 5—5 are rods,—preferably tubular, 70 closed at their outer ends,—the inner ends of which are in communication with the chamber of the vessel 1 and which are rigidly secured to the vessel. The rods 5 are adapted and arranged to slip through the holes 4. 75 It will now be seen that if the door *c* is closed and if the rods 5 be inserted through the holes 4 and locked against withdrawal, the vault-lock will be inaccessible, and the 80 vault door, even if unlocked, cannot be 85 opened without first removing or breaking the vessel 1.

To secure the rods 5 against unauthorized removal, I provide a lock 6, which may be either separate from or integral with the 90 block 2, and which is the same in transverse outline as the block. The lock has therethrough two holes 7—7, which are in alignment with and which form continuations of the holes 4. The rods 5 have, in their inner 95 opposed faces, notches 8, which, when the rods 5 are thrust through the holes 4—8, are automatically engaged by spring-pressed latches 9—9 carried by the lock and controlled by the tumbler 10. This kind of lock 100 is well understood and need not be here further described. When the proper key is inserted in the lock and given a quarter turn, the latches 9 are withdrawn and held from the notches 8, now permitting the withdrawal of the vessel 1 from engagement with the block 2 and the lock 6. It will be seen that the curved walls of the vessel 1 are extended in such fashion that when the vessel 105 is in locked position, the lock 6 and the 110

block 2 are covered and that only the outer end of the lock is exposed.

11 is a tubular projection leading from the chamber of the vessel between the rods 5 and,—when in locked relation,—extending slightly beyond the edge of the door. (See Fig. I.) Should an attempt be made to saw through the rods or to bore through the lock the tube 11 would be ruptured, permitting 10 the escape of the protecting gases.

Having described my invention, what I claim and desire to secure by Letters Patent of the United States, is—

1. In a device for protecting a door 15 against unauthorized opening, a vessel of frangible material, charged with a toxic fluid, and means for detachably locking the vessel on the exterior of the safe across the door opening and in the path of such door,

whereby the vessel is ruptured by the movement of the door.

2. In a device for protecting a door against unauthorized opening, a vessel of frangible material, charged with toxic fluid and adapted to be secured to the door, said vessel projecting at its free end beyond the edge of the door, an apertured block secured to the door joint, rods slidably connected to the vessel, and means for locking said rods in said apertures, whereby the opening of 30 the door will cause said vessel to be fractured.

In testimony whereof I affix my signature in presence of two witnesses.

WALTER C. BECKWITH.
